Attorney.

UNITED STATES PATENT OFFICE.

ALBERT A. KRUMPELMANN, OF ST. PAUL, MINNESOTA.

SPRING-CLAMP.

1,200,953.

Specification of Letters Patent. Patented Oct. 10, 1916.

Application filed September 30, 1915. Serial No. 53,473.

To all whom it may concern:

Be it known that I, ALBERT A. KRUMPELMANN, a citizen of the United States, residing at St. Paul, in the county of Ramsey 5 and State of Minnesota, have invented a new and useful Improvement in Spring-Clamps, of which the following is a specification.

My invention relates to improvements in 10 a spring clamp for holding fillers, pads and filler books, one of the primary objects of which is to eliminate the use of the ordinary pasteboard tongue and cloth binding which it has been customary to use on the fillers 15 and pads.

A further object of my invention is to provide a clamp with a gripping jaw which engages under spring tension the filler or pad when the tongue of the clamp is inserted in a backing or book cover.

My invention further provides means for holding the filler against lateral and longitudinal movement in the cover book or backing.

25 In the drawings which form part of the specification: Figure 1 is a perspective of the spring clamp A and a detail of a filler book B in position to be inserted into the clamp A. Fig. 2 is a perspective of a check 30 book cover C with the filler book B held in place by the clamp A. Fig. 3 is a side elevation of the clamp A. Fig. 4 is a sectional detail view of the backing or cover book C illustrating the clamp A holding the filler 35 B in position on the back C. Fig. 5 is front view of the clamp A illustrating an alternative construction.

The clamp A is formed from a single 40 piece of material, preferably of spring metal and has a tongue 2 and a back 3 bent upward at right angles to the tongue 2 and a forwardly extending jaw 4 which is bent so as to form an acute angle with the back 3. The jaw 4 extends in the same direction 45 as the tongue 2 from the back 3. The outer end of the jaw 4 is turned downward toward the tongue 2 to form a gripping or biting edge 5.

In use the clamp A takes the place of the 50 pasteboard tongue and cloth binding which has heretofore been used on filler books, pads, etc., thus reducing the manufacturing expense of the fillers and pads which can be simply stapled or held together in any

other suitable way when used in connection 55 with the clamp A.

The filler B is inserted into the clamp A from the side as illustrated in Fig. 1 and then the tongue 2 is inserted into the pocket 6 of the backing or cover C forcing the wall 60 7 of the pocket 6 between the filler B and the clamp tongue 2, thus causing the jaw 4 to engage the filler or pad under spring tension and hold it rigid in the cover book as illustrated in Fig. 4.

65 It is obvious that the gripping edge 5 will prevent the filler B from being removed from the clamp A without considerable force.

In the alternative construction illustrated 70 in Fig. 5, downwardly projecting teeth 8 may be provided on the edge 5 which will serve to more positively grip the filler when so desired.

The clamp A does not only take the place 75 of the tongue and cloth binding which has been used heretofore on fillers and pads but serves to hold the same against movement in the cover book or on the backing which may be provided to hold the filler and while 80 other devices have been provided to eliminate the movement of the fillers and pads they have been impractical and expensive, thus making them prohibitive in use with pads and fillers. The simplicity of the 85 clamp A and the elimination of the expense of tongue and binding of the fillers adds to the material value of the clamp A.

While I have illustrated my clamp on an 90 ordinary check book cover and check filler book I do not wish to confine my invention to this particular use but desire to have it understood that it can be carried out in other means and applied to other devices within the scope of the following claims.

95 What I claim is:

1. In a device for holding fillers in combination with a cover or backing for said fillers, a pocket in said cover for removably receiving a clamp, said clamp comprising 100 means formed from a single piece of material for receiving and rigidly gripping a filler to hold the same in said cover against longitudinal removal when said clamp is in position in said pocket.

105 2. In a device for holding fillers in combination with a cover or backing for said fillers, a pocket in said cover for removably

receiving a clamp, said clamp being formed from a single piece of material, having a tongue which is adapted to be inserted into said pocket, a back extending upward at right angles to said tongue, a jaw bent to form an acute angle with said back and extending forwardly therefrom, having its outer edge serrated and turned down toward

said tongue, whereby said clamp is adapted to grip a filler when said tongue is inserted into said pocket and hold said filler against lateral and longitudinal movement.

ALBERT A. KRUMPELMANN.
